(57) **CLAIM**

The ornamental design for a light projection device, as shown and described.

DESCRIPTION

FIG. 1 is a front, top, left perspective view of a light projection device showing my new design therefor;

FIG. 2 is a rear, top, right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

Surfaces provided with surface shading are understood to comprise the claimed design. A broken line abutting a claimed surface is understood to form an unclaimed boundary, and the remaining broken lines are understood to represent portions of the device which forms no part of the claimed design.
